ATTORNEY'S

Patented Apr. 26, 1927.

UNITED STATES PATENT OFFICE.

JEAN MARTIAL LOBIT, OF BROOKLYN, NEW YORK.

FLUE.

Application filed December 6, 1921. Serial No. 520,370.

This invention relates to flues, i. e. to conduits for the passage or conduction of smoke or air or products of combustion.

One of the principal objects of the invention is to provide a flue of such construction that comparatively little rain water or liquid of condensation will flow therethrough even when the top of the flue is exposed to the weather.

Another object is to provide a flue of the above described type in which the draft is unimpeded but rather enhanced. Further objects and advantages will appear as the invention is hereinafter disclosed.

In the drawings:—

Fig. 1 is a vertical section of a form of my invention which may be employed as a chimney cap or ventilator;

Fig. 2 is a section taken on line 2—2 of Fig. 1, and

Fig. 3 is a plan view of the structure shown in Fig. 1.

In the drawings I have illustrated my invention as employed in connection with a chimney or with a ventilator in which the flue is rectangular in cross-section and is provided with baffles to catch and conduct rain water, entering the uppermost section, to the exterior of the flue. The upper hollow section 40 is of sufficiently greater cross-sectional area than the lower hollow section 41 to provide clearance for the egress of water or other liquid. It will be seen that the lower section is provided with ribs 42 which serve to space the upper section therefrom, these ribs being provided with shoulders 43 upon which the lower edge of the upper section rests. The lower section 41 is shown provided with a base flange 44 by which it may be mounted upon and secured to a chimney or ventilator.

A plurality of vertical baffle plates 45, 45 are secured to the interior of the upper section as shown and a trough-shaped drain 45 or gutter 46, 46 provided at the lower edge of each of such baffles. It will be noted that the gutters 46, 46, which are carried by the baffles 45 and upper section 40, slope downwardly from their longitudinal middle portions (see Fig. 2) and are of such length as to conduct any liquid, flowing down the plates 45 and into such gutters, into the clearance opening 50 between the exterior of the section 41 and the interior of the

section 40.

In operation, any rain striking the inside

walls of the section 40 will flow down through the clearance opening 50. Any rain striking the baffles will flow down the same, thence into gutters 46, and thence outwardly through the clearance opening 50. It will therefore be clear that substantially no liquid will enter the section 41 from above.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means within the scope of the appended claims. Also, while it is designed to use the various features and elements in the combination and relation described, some of these may be altered, others omitted and some of the features of each modification embodied in the others without interfering with the more general results outlined and the invention extends to such use within the scope of the appended claims.

What I claim is:—

1. A ventilator comprising in combination, a flue including upper and lower gas-conducting sections, means whereby said upper section is supported by and in series with said lower section, means whereby any liquid flowing down the inside wall of said upper section is discharged exteriorly of said lower section, a baffle extending across the flue above said lower section and means for causing any liquid flowing down said baffle to be discharged exteriorly of said lower section.

2. A ventilator comprising in combination, a flue including a plurality of serially connected gas-conducting sections, said flue being interiorly open for the free transmission of light rays therethrough, a substantially vertical baffle carried by an upper section and extending across the flue, and means whereby any liquid which flows down the inner wall of the last mentioned upper section is discharged to the exterior of the flue before it enters a lower section and means for preventing any liquid which flows down the walls of said baffle from entering a lower section.

In testimony whereof I hereto affix my signature.

JEAN MARTIAL LOBIT.
